CLAIM

The ornamental design for a baby bib, as shown and described.

DESCRIPTION

FIG. 1 is an elevation perspective view of the baby bib of the present invention;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top view thereof;

FIG. 7 is a bottom view thereof;

FIG. 8 is a front elevational view thereof, shown in an environment; and,

FIG. 9 is a right side elevational view thereof.

In the drawings, the broken lines are for the purpose of illustrating environment only and form no part of the claimed design.

1 Claim, 6 Drawing Sheets
